UNITED STATES PATENT OFFICE.

DONALD H. YOST, OF YORK, PENNSYLVANIA.

SPARK-PLUG.

1,132,060.

Specification of Letters Patent. Patented Mar. 16, 1915.

Application filed September 18, 1912. Serial No. 721,167.

To all whom it may concern:

Be it known that I, DONALD H. YOST, a citizen of the United States, residing in the city of York, county of York, State of Pennsylvania, have invented certain new and useful Improvements in Spark-Plugs, of which the following is a specification.

My invention relates to improvements in spark plugs adapted for use in igniting the gas in internal combustion engines or the like. In devices of this character it has been found that from one cause or another particles of carbon are deposited upon the electrodes with the result that efficient operation is prevented.

It is the object of my invention to provide a spark plug having an improved and novel construction of electrode by the employment of which the deposition of an undue amount of carbon thereon is prevented.

In the construction of a spark plug embodying the advantageous and novel features of construction of my invention, I employ a pendulum as one of the electrodes which is supported in operative relation to the other electrode. By the employment of a pendulum construction of electrode I have been able to prevent the undue and ruinous deposition of carbon and thereby have enhanced the efficiency of spark plugs.

In order that the novel features of my invention may be understood and the same fully comprehended, I have illustrated one form of a convenient embodiment thereof in the accompanying drawings, in which,—

Figure 1 is a central longitudinal sectional view in a horizontal plane of a spark plug provided with a pendulum electrode which is shown as being extended in the direction of the axis of the plug; Fig. 2 is an elevational view of the same looking toward the left of Fig. 1, the said plug being turned, however, toward the left to a position at right angles to the position in which it is shown in Fig. 1 and the pendulum electrode being indicated in a plurality of positions; and Fig. 3 is a view in side elevation looking toward the left in Fig. 1, the pendulum electrode being shown, however, in a depending position.

Referring to the drawings, 1 designates a stationary member adapted to be secured in the side wall of a gas engine or other like apparatus by means of the screw-threads 2 which are shown upon one end portion thereof.

3 designates a sleeve of insulating material, such as porcelain, which extends through the said stationary member 1 and which is secured therein by means of a thin metallic sleeve 4; an interposed layer of cement or other securing means 5; and a screw plug 6 having screw-threaded engagement with the interior of the outer end of the stationary member 1.

7 designates a rod which extends through the insulating sleeve 3, its inner end projecting beyond the inner end of the said sleeve, as shown at 8, and constituting one of the electrodes of the device. The outer end of the rod 7 has connection with a screw-threaded projection 10 to which a binding nut 11 is adapted to be secured in a known manner and for a known purpose.

The portion of the spark plug and their arrangement with relation to each other as thus far described are of known construction and are referred to for the purpose of a better understanding of my invention, a description of which follows hereinafter.

12 designates a supporting member of any suitable material which is permanently secured in any desired manner to the inner end of the stationary member 1.

In the construction shown I have illustrated the member 1 as being provided with a slightly tapered hole 13 which receives the correspondingly tapered end portion of the member 12, the latter being permanently secured in position. The outer end 20 portion 14 of the member 12 is bent at right angles to the axis of the sleeve 3 and the rod 7 and is extended cross-wise of the same and in front of the end thereof as shown in the drawings.

Pivoted upon the transversely extended portion 14 is a pendulum 15, the outer or free end of which is provided with a pendulum bob 16 as usual. The pivoted end of the said pendulum is provided with a disk-like part 17 which constitutes one of the electrodes of my device. The inner end of the spark plug is located interiorly of the engine and the electric discharges to produce the ignition sparks take place between the end 8 of the rod 7 and a large proportion of the periphery of the disk-like part 17. In order to provide the pivoted end of the said pendulum with an extended bearing I have formed the same with a sleeve 18 which 110 abuts a collar 19 upon the transversely extended portion 14 of the electrode support.

The electrode is secured upon the transversely extending portion 14 by means of a washer 20 and an upset portion 21 upon the end of the said transversely extending portion.

Preferably the spark plug is fitted and secured in position in the wall of the engine or like apparatus so that the transversely extended portion 14 of the electrode support 10 occupies a horizontal position so that the pendulum is such that in swinging about its pivot it will strike the edge of the inner end portion of the stationary member 1 at opposite points as indicated in Fig. 2 of the drawings.

Upon reference to Fig. 3 of the drawings, it is clear to be seen that the portion 14 of the electrode support occupies a horizontal position and it will be understood that if the 20 plug should be turned through a distance of 180 degrees the said support would still occupy such horizontal position.

It will be seen that the pendulum is limited in its movements and that instead of 25 revolving entirely around its support it swings through the arc of a circle as is indicated in Fig. 2 of the drawings.

By providing the disk 17 with a depending weight as is illustrated; in other words, 30 by employing a pendulum as one of the electrodes, I secure means whereby a substantial pivotal movement of one of the electrodes about its support, due to the vibratory action of the engine and to the inrush and explosion of the gases, is made certain. One 35 reason for this is that whenever through any cause the pivoted electrode is swung to a position other than its normally depending position, its return to normal position is preceded by a period of oscillatory movements 40 due to the influence of gravity and the momentum of the pendulum.

I claim:—

1. A spark plug having means projecting forwardly from the body portion thereof 45 and also having electrodes one of which is stationary with respect to the body structure of the said plug and the other one of which consists of a disk-like movable member loosely pivoted to said projecting means and 50 having a depending weight connected thereto, the said disk-like member occupying a position in operative relation to the said stationary electrode.

2. A spark plug having a projection and 55 electrodes, one of which electrodes consists of a disk-like oscillatable member loosely pivoted on said projection and having a depending weight integrally connected therewith, the said movable disk-like member 60 occupying a position in operative relation to the other electrode.

3. A spark plug comprising a stationary body portion, a stationary electrode axially situated with respect to said stationary member, an elongated oscillatory electrode pivotally supported at one end in axial alignment with the said stationary member, the other end of the said elongated oscillatory electrode normally occupying a depending 70 position and the said depending end being arrested by said stationary member at opposite ends of the path of oscillation to prevent complete revolution of the said oscillatory pivoted electrode.

In testimony that I claim the foregoing as my invention, I have hereunto signed my name this 16th day of September, A. D. 75 1912.

DONALD H. YOST.

In the presence of—

RICHARD F. YOST,
FRED R. YOST.
